Term of patent 14 years

Int. Cl. D24—02

U.S. Cl. D24—1 A

FIG. 1 is a perspective view of a double tubing unit for a water cooled dental impression tray showing my new design;

FIG. 2 is top plan view thereof, with portions omitted and the tubing broken away for ease of illustration; and

FIG. 3 is a cross-section taken on line 3—3 of FIG. 2.

The broken lines representing the impression tray are shown for illustrative purposes only.

I claim:

The ornamental design for a double tubing unit for a water cooled dental impression tray, as shown and described.
